DESIGN FOR AN EMBOSSED LEATHER

Leonard I. Freedman, Brooklyn, N. Y.

Application May 4, 1944, Serial No. 113,470

Term of patent 7 years

(Cl. D87—3)

To all whom it may concern:

Be it known that I, Leonard I. Freedman, a citizen of the United States of America, residing in Brooklyn, county of Kings, and State of New York, have invented a new, original, and ornamental Design for an Embossed Leather, of which the following is a specification, reference being had to the accompanying drawing, forming part thereof.

The figure on the drawing is a plan view of an embossed leather showing my new design.

The design unit is contained between the dot and dash lines which unit is repeated horizontally in regular succession as indicated by the extensions beyond the unit boundaries.

I claim:

The ornamental design for an embossed leather, substantially as shown and described.

LEONARD I. FREEDMAN.
